[57] CLAIM

The ornamental design for a can body, as shown and
described.

DESCRIPTION

FIG. 1 is an elevational view of a can body showing our
new design, the opposite side being the same in appear-
ance;

FIG. 2 is a top plan view; and

FIG. 3 is an enlarged fragmentary view of the upper
right corner.

FIG. 1.

FIG. 3.

FIG. 2.
